UNITED STATES PATENT OFFICE.

KATHERINE D. JEWELL, OF ST. PAUL, MINNESOTA.

ROUGE AND POWDER PUFF.

Application filed May 5, 1927. Serial No. 188,960.

The present invention relates to a rouge or powder puff, and is particularly adapted to the construction of small puffs, such as are commonly carried in small compacts and vanity cases.

The difficulty in making a small rouge and powder puff which will distribute the material evenly and smoothly upon the face is that in making the puff, which must necessarily be of limited thickness, if a stiffening member such as the customary cardboard disk is used over the entire area of the puff, the construction will be so rigid that the material is distributed only around the edges of the puff and the stiffness of the device makes it unpleasant to use, whereas, if the puff is made flexible, the edges curl back leaving only a small area in the center available for use.

An object of the present invention is to make a rouge and powder puff having a resilient plate imbedded therein, said plate terminating short of the edges of the puff to retain the puff in shape and provide for an even distribution of material thereby.

In order to attain this object there is provided in accordance with one feature of the invention, a powder puff having a face of piled fabric and having a fabric back with a plate of resilient material having a pad connected to the forward face thereof, the pad, the resilient plate, and the fabric back being all connected to a handle member to hold the parts in position.

These and other features of the invention will be more fully brought out in the following description and the accompanying drawings, wherein:

Figure 1, is a view in perspective of an assembled puff made in accordance with the present invention.

Figure 2, is a reduced view in transverse section of the device shown in Figure 1.

Figure 3, is a sectional view taken at right angles to the view shown in Figure 2, the fabric back member and parts connected thereto being removed from engagement with the piled fabric front portion.

Figure 4, is an enlarged view of a resilient disk mounted within the puff; and

Figure 5, is a view in transverse section of the device shown in Figure 4.

Referring to the drawings in detail, a circular piece 1 of piled fabric is formed somewhat larger than the finished diameter of

the puff. A smaller circular piece 2 of fabric, such as silk, is then formed, and to the lower surface of this member is connected in turn a disk 3 of thin, flexible material, such as celluloid, and a circular pad 4 of material, such as cotton. A handle 5, which may be a small ring, is then sewn, or otherwise connected, to the upper fabric member 2, the celluloid disk 3 and the pad 4. The thread or other fastening means is passed through holes 6 and 7 in the celluloid disk 3. The edge of the piled fabric 1 is then turned inwardly throughout its entire circumference and is sewn to the fabric member 2 around its outer edge. The celluloid member 3 is preferably made thin enough so that it may bend easily when applying rouge or powder to the face, and by making the celluloid disk of smaller diameter than the puff, the outer edges are free to turn back while the thin celluloid sheet holds the pad in resilient contact with the face. By permitting a slight resilient displacement of the puff an even distribution is provided throughout the entire area thereof, and, since the celluloid, returns to its original shape upon releasing the pressure of application, the puff retains its original form throughout the entire life of the pile fabric. While the device is illustrated for a small puff of compact size, the device would be equally suited for the construction of a larger puff.

I claim:

1. A rouge and powder puff of the character described, comprising a back member having a resilient disk and a pad member connected thereto, and having a piled fabric front member connected to said back member above the outer edge thereof.

2. A rouge and powder puff of the character described, having a circular fabric back member, a circular resilient celluloid disk of smaller diameter than said fabric disk positioned forwardly of said fabric member, a pad member positioned forwardly of said celluloid disk, a handle fastened to said fabric member, said fastening means passing through said celluloid disk and said pad to unite them with said fabric member, and a circular piled fabric front member connected to said fabric member about the circumference thereof to enclose said celluloid disk in said pad.

In testimony whereof I affix my signature.

KATHERINE D. JEWELL.
